MAGNETIC MOLD COVER RETAINER

Sigurd Clausen, Brooklyn, and William C. Broekhuysen, Garden City, N. Y., assignors to International Cigar Machinery Company, a corporation of New Jersey

Application February 6, 1941, Serial No. 377,604

17 Claims. (Cl. 131—87)

This invention relates to a cigar machine, and more particularly to an improvement in cigar bunch shaping mechanism. It has special reference to improvements in the construction of molds and covers therefor, and especially to the cover securing means.

Cigar bunch shaping devices are frequently made up of a plurality of shaping pockets having covers associated therewith for shaping cigar bunches inserted into said pockets. These pockets travel over a fixed path, and during this period of travel various types of mechanical holding means have been provided in the past for holding said members together. Although these devices have usually performed their functions satisfactorily, it has been found that mechanical devices are subject to wear and tear which necessitates their replacement from time to time.

This is true where a circumferential ringlike pathway such as that shown in U. S. Patent No. 1,838,157, granted December 29, 1931 to R. E. Rundell, is used for holding the covers in shaping relation with the pockets of an intermittently rotating turret. When the rollers and pathway have become worn with use, the male covers are no longer pushed snugly into the female pockets, and as a result the shaping pockets become larger and larger the longer the mechanism is used. A machine using a mechanical cover retaining device will also have a certain amount of noise resulting therefrom and in addition will come into contact with various small pieces of tobacco causing it to accumulate gum, which must be removed in order to keep the cigar machine in good operating condition.

Where a cigar is being made with a straight tuck, as opposed to a tapered tuck, a cover retaining device such as that disclosed in the above mentioned patent may cause the covers to slide axially which damages the cigar undergoing shaping.

It is therefore an object of the instant invention to eliminate the mechanical cover securing means used to hold the cigar shaping pocket and cover members together. This will not only result in a decrease in the amount of noise caused by an operating cigar machine, but will also avoid the accumulation of tobacco gum upon any moving parts thereby avoiding the necessity of frequent cleaning. Since mechanical parts which might cause the covers to slide axially on the pocket have been eliminated, cigars having a straight tuck can be shaped as readily as cigars having a tapered tuck.

A further object is to utilize magnetic means for securing a cover to a cigar shaping pocket. It is also an object to construct cover securing means in such a manner that foreign magnetic material will not accumulate on the shaping pockets and covers.

Another object is to provide a cover securing means which may have its securing force nullified periodically in order to facilitate the removal and replacement of the cover on the pocket.

An additional object is to provide a simplified cover securing device which will eliminate the use of a considerable number of interengaging parts for securing a shaping cover to a shaping pocket.

Other objects and features of the invention will appear as the description of the particular physical embodiment selected to illustrate the invention progresses.

In the accompanying drawings, which form a part of this specification, like characters of reference have been applied to corresponding parts throughout the several views which make up the drawings, in which:

Fig. 1 is a side elevation partly in section of a portion of a cigar bunch shaper turret equipped with electro-magnets which normally retain the mold covers in position;

Fig. 2 is a sectional side elevation of the turret and in addition shows the mold cover removing apparatus;

Fig. 3 is a sectional view taken from line 3—3 of Fig. 1 of the electro-magnet mounting;

Fig. 4 is a sectional end elevation of a modified type of turret having permanent magnets for holding the mold covers in position;

Fig. 5 illustrates another modified form in which the mold covers carry a series of permanent magnets;

Fig. 6 is a sectional end view of the same taken from line 6—6 of Fig. 5;

Fig. 7 is a side elevation partly in section of a modified form of turret corresponding to Fig. 4; and Fig. 8 is a side elevation partly in section of a modified form of turret corresponding to Figs. 5 and 6.

Referring to Figs. 1 and 2, the side bracket 10 of the machine supports a shaft 11 of a turret 12 which is intermittently rotated by an indexing device 13 of the type described in U. S. Patent No. 1,838,157, granted December 29, 1931 to R. E. Rundell. The bracket 10 also supports a shaft 14, on which swings a cover removing arm 15.

The turret consists of the cylindrical shell 12

made of magnetic material, to which are fastened the female sections 16 of the concentrators or cigar shaping and molding members, there being a circular group of complementary male and female cigar bunch concentrator shaping sections on the turret. The male sections 17 are attached to plates 18 which in turn are secured to holders 19 provided with rollers 20 which enter guide tracks formed in the frames 20a and 20b supported by rod 20c. The frames 20a and 20b are similar in construction to the pathways 23 of the above mentioned Rundell patent and are similarly provided with openings at the top of the turret through which the male sections are removed in a manner to be presently described. The female sections 16 and the male sections 17 of the molding members are made of non-magnetic material.

The turret is rotated in a step-by-step motion by the indexing device 13 which is operated by a cam actuated rod 21 connected to one arm of a bell crank lever 22 fulcrumed on an arm 22a loosely mounted on shaft 11, the other arm of lever 22 carrying a lock 23 engaging the slots of the indexing device 13. Since the lock 23 is operated in and out of engagement with the slots of the index, in the same manner as described in the above mentioned patent, a detailed description of the same in the present case is omitted in the interest of brevity. The rod 21 is actuated by a cam (not shown) mounted on a cam shaft (not shown) of the machine.

In order to hold the shaping members 16 and 17 in shaping relationship, an electro-magnet is provided on each side of the female sections 16. The fact that applicant has shown the electro-magnets as being mounted beside the female section 16 does not mean that they cannot be mounted elsewhere to produce the same result. Each electro-magnet consists of a coil 27, a core 26, and a plate 24. Said members making up the electro-magnet are elongated and extend the full length of the "concentrators" 16.

The fact that applicant has shown the magnetic flux in a certain path does not mean that the construction cannot be varied to change the path of the magnetic flux, and any such variations are intended to come within the scope of this specification and subjoined claims.

The coils 27 of each pair of electro-magnets adjacent a pocket are wound oppositely so that the plate 18 of the male section will engage a north pole on one magnet and a south pole on the other magnet, which electro-magnets are located on opposite sides of a female pocket as shown in Fig. 1. Although the turret may be made of a non-magnetic material without nullifying the retaining force of said magnets, it is preferable to make it of a magnetic material so that the flux will be complete and a greater drawing and securing result obtained. Where the north and south poles are located on the same side of the magnet, as mentioned heretofore, this problem does not enter in and the turret 12 can be non-magnetic without having any effect on the securing force exerted by the electro-magnets.

The plates 24 are held in place by screws 25 passing through the core 26 of the electro-magnets and threading into the turret. The plates 24 are beveled at the ends to reduce the short circuited flux to a minimum and still prevent the entrance of dirt and foreign matter into the electro-magnet. Shields 83 positioned between plates 24 are also a protection against dirt and foreign

matter and are made of a non-magnetic material such as aluminum. Each pair of magnets is connected in series by a wire 28 and has one lead 29 grounded to the turret 12 and the other lead 30 connected to a brush 31 riding on an insulated stationary contact ring 32 which by a wire 33 is connected to one D. C. terminal of a rectifier 34 having its other terminal grounded. A segment 35 is insulated from the ring 32 and connects by a wire 36 to one side of a switch 37 having a wire 38 connecting to the D. C. supply.

The normally closed switch 37 is equipped with a cam roller 39 actuated by a cam 40 mounted on cam shaft 84. As the turret advances the concentrators one station and dwells, the cam 40 has completed one cycle, thus causing its raised portion 41 to engage the cam roller 39 and operate the switch, thus opening the circuit leading to segment 35 and thereby de-energizing one pair of electro-magnets 27 so that the male section of its associated concentrator can be removed from the turret. The de-energizing and re-energizing features shown may of course be omitted. A suitable cover removing member such as 15, to be presently described, will then exert a force sufficient to remove the cover 17 from the pocket 16 and thereby overcome the securing force exerted by the magnets. The removal of the male section in the present case occurs when the concentrators are in their uppermost or 12 o'clock position.

The current (D. C.) for energizing the magnets may be obtained from any convenient source such as a rectifier 34 or a generator.

The brushes 31 are carried by a holder 42 (Fig. 2) fastened to the turret 12 and are held in engagement with the ring 32 and segment 35 by springs 43 tensioned by nuts 44. The members 32 and 35 are secured to a stationary holder 45 carried by a support 46 of the machine.

The magnetic holding means of each male concentrator is released as it reaches its uppermost position in the turret so that it can be removed for the purpose of discharging the concentrated bunch and of receiving an unconcentrated bunch. The removal of the male sections is accomplished by the swinging arm 15 loosely fulcrumed on the shaft 14 and having a slide bar 50 which is hinged to an arm 51 pinned to the shaft 14. The slide bar 50 is confined in the slideway of arm 15 by guide strips 52 and has fingers 53 which engage slots 54 provided for this purpose in the male section holders 19 and normally held in locked position by the springs 55, the latter holding the arms 15, 51 separated. The shaft 14 is provided with a crank 56 which receives reciprocating motion from a cam lever (not shown) through a rod 57.

The arm 15 is provided with channeled end pieces 58 into which the rollers 20 of the male sections 17 roll as a concentrator approaches its uppermost position. The male sections are securely locked in the arm 15 by the fingers 53 when the arm 51 is held away from the arm 15 by the springs 55. As soon however as the arm 51 is pushed against the arm 15, which occurs when the crank 56 keeps on moving after the arm 15 has come to rest on the turret with the concentrator closed, the slide bar 50 moves out and disengages the fingers 53 from the slots 54.

Since the operation of the cover removing and replacing arm 15 is substantially similar to that shown in the Rundell patent above referred to, a

further detailed description has been omitted for the sake of brevity.

Figs. 4 and 7 illustrate a modified form of the present invention and disclose how permanent magnets might be utilized for holding the mold covers in place instead of electro-magnets.

A turret 77 made of a magnetic material such as cast iron is provided with spaced flat portions 60 to support the female sections 73. Said turret also is provided with flat surfaces 61 adjacent surface 60 to support the base of permanent magnets 62 (which may be formed of a ferrous alloy containing aluminum, nickel and cobalt in the approximate proportions of 12% Al, 20% Ni and 5% Co, the remainder being Fe with fractional percentages of C, Mn and Si, and commonly known as "Alnico") placed at each side of the female sections 73. The magnets at their upper end are notched at 63 to engage correspondingly shaped notches in the concentrators 73, thereby providing means for holding the magnets in position when locked by clamp plates 64 which are made of a non-magnetic material such as aluminum. The male sections 74 are attached to plates 75 which may be made of a magnetic material such as cold rolled steel and have rollers 76 which are guided in the tracks of members 76a and 76b and adapted to engage channeled end pieces of arm 115, when the rollers enter the openings (not shown) in the members 76a and 76b at the top of the turret, so that plates 75 may be pulled away from the permanent magnets 62, thereby separating the male sections 74 from the female sections 73. The female sections 73 and the male sections 74 are made of a non-magnetic material. The plates 75 are provided with slotted lugs 75a corresponding to the slotted portions 54 shown in Fig. 2. The turret 77 is fastened to a shaft 211 rotatably mounted in a side bracket 210. Shaft 211 carries an indexing device 213 similar to device 13 shown in Figure 2 and similarly operated by a lock 223 carried by one arm of a bell crank lever 222 fulcrumed on an arm 222a loosely mounted on shaft 211, the other arm of lever 222 being connected to a cam actuated rod 221. Arm 115 is loosely mounted on a shaft 114 supported in bracket 210 and has a slide bar 150 confined in a slideway of arm 115 by guide strips 152 and connected to arm 151 fastened on shaft 114. The latter is provided with an arm 156 operated by a connecting rod 157. Arm 115 is provided with channeled end pieces 158 into which the rollers 76 enter as the concentrator approaches its uppermost position. The male sections are locked to the arm 115 by the engagement of the slotted lugs 75a with the fingers 153 on slide bar 150 when the arm 151 is moved away from arm 115 by the spring 155. When the arm 151 is moved toward the arm 115, which occurs when the arm 156 keeps on moving after the arm 115 has returned the concentrator to the top of the turret, the slide bar continues moving and disengages the fingers 153 from the lugs 75a. Since the covering removing means is similar to that shown in Fig. 2, further description thereof is deemed unnecessary. The male sections can be removed by any other suitable means also, such as that disclosed in U. S. Patent No. 2,157,537, granted May 9, 1939 to H. H. Wheeler.

Figs. 5, 6, and 8 illustrate another modified form of the present invention and disclose another way for utilizing permanent magnets for securing mold covers to a cigar shaping turret.

A turret 78 made of a magnetic material such

as cast iron carries a plurality of female sections 79 made of a non-magnetic material. A corresponding male section 80 also made of non-magnetic material is provided for each female section 79 and is attached to a non-magnetic plate 81. The plate 81 is provided with a number of cutout portions 70 to receive the rounded permanent magnets 71 which may also be made of "Alnico," said magnets being secured to the non-magnetic plate 81 and male section 80 by screws 72. Plate 81 is provided with slotted lugs 81a corresponding to the lugs 54 shown in Fig. 2, and carries rollers 82 adapted to be engaged by a cover removing means which will pull the rounded permanent magnets 71 together with the male section 80 from the turret 78 and the female section 79. The rollers 82 of the male sections are guided in tracks formed in members 82a and 82b supported by rod 82c. The members 82a and 82c have openings at the top of the turret to permit the sections to be removed and replaced from the turret.

The turret 78 is fastened on a shaft 211 rotatably mounted in a side bracket 210 and provided with an indexing device 213 fastened thereon and operated by a lock 223 carried by one arm of a bell crank lever 222 carried by an arm 222a loosely mounted on shaft 211, the other arm of lever 222 being operated by cam actuated rod 221. Since the operation of the indexing device is similar to that of the indexing device shown in the above mentioned Rundell patent, further description thereof is deemed unnecessary. The cover removing means is shown in Fig. 8 and consists of an arm 215 loosely mounted on the shaft 214 carried by bracket 210. In a slide-way of arm 215 is slidably mounted a bar 250 connected to a link 251 fastened on shaft 214. Slide bar 250 is confined in the slide-way 40 of arm 215 by strips 252 and is provided with fingers 253 which engage the lugs 81a of the male sections and are normally held in locked position by the spring 255. The shaft 214 also carries an arm 256 operated by a connecting rod 257. The arm 215 is provided with channeled end pieces 258 which receive the rollers 82 of the uppermost male section. This male section is locked to the arm 215 by the engagement of fingers 253 with lugs 81a, when the arm 215 is moved away from the arm 214 by spring 255. When the arm 215 is moved toward the arm 214, which occurs when the arm 215 keeps on moving after the arm 215 has returned the male section to the top of the turret, the slide bar continues moving and disengages the fingers 253 from the lugs 81a. Then the turret advances the next male section into position wherein its rollers 82 enter the end pieces 258 and the arm 215 is lifted and the lugs 81a are engaged by the fingers 253 and the male section is thereby locked in position as it is lifted.

The invention above described may be varied in construction within the scope of the claims, for the particular device selected to illustrate the invention is but one of many concrete embodiments of the same. The invention therefore is not to be restricted to the precise details of the structure shown and described.

What is claimed is:

1. The combination with a group of complementary male and female cigar bunch concentrator sections intermittently rotating about a horizontal axis, of a plurality of electro-magnets for holding said sections together during group rotation, means for successively removing and

replacing the male sections at a bunch receiving and discharging position, means for de-energizing and re-energizing the electro-magnets at bunch receiving and discharging position in timed relation with the cover removing and replacing means.

2. In a cigar machine, bunch shaping mechanism comprising a turret, a cigar bunch shaping pocket connected to said turret, a complementary shaping cover arranged to coact with said cigar bunch shaping pocket to shape bunches, electro-magnets connected to said turret and positioned to secure said shaping cover to the cigar bunch shaping pocket, an electric circuit connected to said electro-magnets for energizing said electro-magnets, and means for removing and replacing said cover on said pocket, and a device for intermittently breaking said circuit to deenergize said electro-magnets in timed relation to the operation of said means.

3. In a cigar machine, a cigar bunch shaping device comprising a turret of magnetic material, a cigar bunch shaping pocket of non-magnetic material connected to said turret, a plate of magnetic material, a complementary shaping cover of non-magnetic material connected to said plate and arranged to coact with said shaping pocket to shape bunches therein, permanent magnets connected to said turret and positioned so as to engage said plate to secure the cover in shaping position on said pocket, projecting elements connected to said plate, and a device arranged to engage said projecting elements for removing and replacing said cover on said pocket.

4. In a cigar shaping mechanism, the combination with a turret composed of magnetic material and provided with a plurality of pockets of non-magnetic material, a cover composed of non-magnetic material for coaction with said pockets for molding bunches therein, a member made of magnetic material connected to said cover, a pair of electro-magnets associated with said turret and arranged to connect with said member to secure the covers to said pockets when energized, means for removing and replacing said covers, and means for deenergizing and re-energizing said electro-magnets in timed relation with said cover removing and replacing means.

5. In a cigar bunch shaping mechanism, the combination with a turret composed of magnetic material, of a plurality of non-magnetic pockets connected to said turret, covers of non-magnetic material coacting with said pockets for molding bunches in said pockets, permanent magnets connected to said covers and formed so as to attach themselves to said turret to secure said covers to said pockets, and means for engaging said covers for removing and replacing the same.

6. A cigar bunch shaping mechanism comprising a turret, cigar bunch shaping pockets of non-magnetic material connected to said turret, covers of non-magnetic material adapted to coact with said pockets to shape a cigar bunch located therein, magnetic members associated with said covers, electro-magnets connected to said turret and positioned to engage said magnetic members to secure each of said covers to each of said pockets, and a control circuit for energizing and de-energizing said electro-magnets to allow the removal and replacement of one of said covers on one of said pockets at a time.

7. In a cigar machine, the combination with an intermittently revolving turret, of complementary male and female cigar bunch shaping sec-

tions transversely mounted thereon, magnetic means operating along the major portion of the length of said sections for holding the sections together during travel, and means for separating said sections at a cigar bunch receiving and discharging station.

8. In a cigar shaping mechanism, the combination with a turret provided with a plurality of pockets and covers coacting with said pockets for molding bunches in said pockets, of electro-magnetic means positioned adjacent to said pockets, members made of magnetic material connected to said covers and arranged to come into engagement with said electro-magnetic means, a device for removing and replacing said covers on said pockets, and means for de-energizing said electro-magnetic means to allow the removal and replacement of said covers on said pockets and energizing said electro-magnetic means to secure the covers to said pockets.

9. The combination with an intermittently rotatable turret provided with a plurality of mold pockets about its periphery, of a plurality of complementary covers coacting with said pockets to shape bunches located therein, magnetic members connected to each of said covers, a plurality of electro-magnets connected to the sides of each of said pockets for holding said covers on said pockets by attracting said magnetic members, cover removing members associated with said covers, a transfer cooperating with said turret for engaging said cover removing members to remove and replace covers on said pockets, and means for energizing said magnets to secure said covers to said pockets during rotation of said turret and de-energizing the magnets adjacent each of said pockets consecutively to allow said covers to be removed.

10. The combination with an intermittently rotating turret provided with a series of mold pockets spaced about its periphery, of a plurality of bunch shaping covers cooperating with said mold pockets for shaping bunches lodged therein, a plurality of electro-magnets for holding said covers on said pockets during rotation of said turret, means for energizing said magnets, cover removing means carried by said covers, a cover removing and replacing transfer adapted to engage said cover removing means to permit the removal of a shaped cigar bunch and the insertion of an unshaped cigar bunch, and a control circuit for de-energizing said electro-magnets in timed relation with said transfer to release said covers from said pockets.

11. The combination with an intermittently rotatable turret provided with a plurality of spaced pockets around its periphery, of a plurality of permanent magnets disposed adjacent to each of said pockets, said magnets being formed of a ferrous alloy containing aluminum, nickel and cobalt in the approximate proportions of aluminum 12%, nickel 20% and cobalt 5% and commonly known as "Alnico"; a plurality of complementary covers cooperating with said pockets for shaping cigar bunches located therein; a plurality of members made of magnetic material connected to each of said covers and adapted to engage with said magnets for securing said covers to said pockets; and cover removing mechanism adapted to engage and remove said covers at pocket unloading position.

12. In a cigar machine, a rotatable turret, a plurality of mold pockets removably mounted on said turret and about the periphery thereof, per-

manent magnets connected to said turret and located adjacent to said pockets, a plurality of mold covers adapted to coact with said mold pockets, and elements made of a magnetic material connected to each of said covers and arranged to engage with said magnets to secure said covers to said pockets and to mold a cigar bunch located therein.

13. In a cigar machine, a rotatable turret made of a magnetic material, a plurality of mold pockets removably mounted on said turret and about the periphery thereof, pocket closing covers adapted to engage in shaping relationship with said pockets to mold cigar bunches located therein, and permanent magnets connected to said covers, said magnets being constructed and arranged to engage with said turret to hold said covers fast to said mold pockets.

14. In a cigar machine, a device for molding cigar bunches comprising, a support made of magnetic material, a plurality of mold pockets for shaping cigar bunches connected to said support, pocket closing covers adapted to engage in shaping relationship with said pockets to mold a cigar bunch located therein, a plurality of permanent magnets connected to said covers and constructed and arranged to attach themselves to said support for securing said covers to said pockets, and means for removing and replacing said covers consecutively to allow the removal of molded cigar bunches and the insertion of unmolded cigar bunches in said molding pockets.

15. The combination with a group of complementary pocket and cover members for shaping cigar bunches, of magnetic means operating along the major portion of the length of said members

5 for securing said covers in shaping position relative to said pockets, a device for removing said covers from said pockets, and means for nullifying the securing force exerted by said magnetic means to permit said covers to be removed.

16. In a cigar machine, a device for shaping cigar bunches comprising, an endless traveling support, a plurality of pockets for shaping cigar bunches connected to said support, pocket closing covers adapted to engage in shaping relationship with said pocket to shape a cigar bunch located therein, means acting along the major portion of the length of said pockets for attracting said covers to said pockets into bunch forming relationship, and means for removing and replacing said covers to allow the removal of shaped cigar bunches and the insertion of unshaped cigar bunches in said shaping pockets.

20 17. In a cigar machine, a device for molding cigar bunches comprising, an endless intermittently moving support, a plurality of mold pockets for shaping cigar bunches connected to said support, pocket closing covers adapted to engage in shaping relationship with said pocket to mold a cigar bunch therein, complementary magnetic means connected to said covers and to said support, said magnetic means coacting along the major portion of the length of said pockets to hold said pockets and covers in cigar shaping relationship, and means for removing and replacing said covers consecutively to allow the removal of molded cigar bunches and the insertion of unmolded cigar bunches in said molding pockets.
